ARTICLE HOLDING CLAMP OR THE LIKE

George H. Davis, Jr., Oakmont, Pa.

Application July 11, 1952, Serial No. 20,565

Term of patent 14 years

(Cl. D17—3)

To all whom it may concern:

Be it known that I, George H. Davis, Jr., a citizen of the United States, residing in Oakmont, in the county of Allegheny and State of Pennsylvania, have invented a new, original, and ornamental Design for an Article Holding Clamp or the like, of which the following is a specification, reference being had to the accompanying drawing, forming part thereof.

Figure 1 is a perspective view of an article holding clamp or the like, showing my new design, with the clamp in partially open position;

Figure 2 is a plan view of the same;

Figure 3 is a side elevation showing the clamp in closed position;

Figure 4 is a side elevation of Figure 1.

I claim:

The ornamental design for an article holding clamp or the like, as shown.
